UNITED STATES PATENT OFFICE.

WILLIAM F. TROAST AND SAMUEL R. SLAYMAKER, OF LANCASTER, PENNSYLVANIA, ASSIGNORS TO SLAYMAKER, BARRY & CO., OF SAME PLACE.

PADLOCK.

SPECIFICATION forming part of Letters Patent No. 513,160, dated January 23, 1894.

Application filed September 5, 1892. Serial No. 445,142. (No model.)

To all whom it may concern:

Be it known that we, WILLIAM F. TROAST and SAMUEL R. SLAYMAKER, citizens of the United States, residing in Lancaster, in the 5 county of Lancaster and State of Pennsylvania, have invented certain Improvements in Padlocks, of which the following is a specification.

This invention relates to improvements in 10 that class of padlocks in which one end of a U-shaped shackle is pivoted in the case; and the objects of the invention are, first, to guard more thoroughly against the surreptitious 15 opening of the lock than is done in the padlocks now in use; and second, to prevent transverse motion of the swinging end of the shackle when locked in the case.

The invention consists in the construction 20 and combination of the various parts, as hereinafter fully described, and then specifically pointed out in the claims.

In the accompanying drawings, which form a part of this specification, Figure 1 is a bottom perspective view of the body of the case, 25 the cap being removed and the operating mechanism shown in place with the shackle locked in the case. Fig. 2 is a top perspective view of the body of the case, showing the operating mechanism in place, the swinging end of the shackle locked therein and the 30 top plate of the case cut away to show the position of the bolt-spring. Fig. 3 is a perspective bottom view of the same part of the case, showing the shackle opened out and the plunger head in position in front of the bolt. Fig. 4 is a top perspective view, showing the 35 shackle opened out and the top plate cut away to show the position of the bolt-spring when the shackle is so opened. Fig. 5 is a perspective view of the body of the case, 40 showing the operating parts removed. Fig. 6 is a similar view of the cap, as seen from the top. Fig. 7 is a lower side perspective view of the bolt, and Fig. 8 an upper side 45 perspective view thereof. Fig. 9 is a perspective view of the plunger.

Similar letters and figures indicate like parts throughout the several views.

The lock-case is divided edgewise or approximately so, through the center, one side A, called the body of the case for the pur-

poses of this specification, having the rivet pins a and a' formed therewith and the operating mechanism located therein. The "fast" limb of the shackle B is pivoted on 55 rivet-pin a', and the space occupied by the end of said "fast" limb is separated from the body by registering walls E, formed about said space in the body A and cap A'. (The portion A' is called the cap for the purposes 60 of this specification.) These walls prevent the entrance of any foreign matter into the case through the spaces between the said "fast" end of the shackle and the sides of the case. The swinging end of the shackle has 65 a reduced end b, in the inner edge of which there is formed a notch b'. In the upper end of the case there is a channel formed between the top plate a² of the body of the case and a wall 9, f and 10 therein and a wall 23 registering therewith formed with cap A'. In this channel there is placed a locking-bolt C. Bolt 70 C is of peculiar construction. In the lower face there is an oval opening 1, in the upper right-hand corner of which is formed a shoulder 2, as shown in Fig. 7, adapted to be engaged by a ward of the key to force the bolt C back out of engagement with the shackle. The upper end of opening 1 is partially covered by flanges or partitions 3, forming a 75 winged-opening between them through which the heel of the key passes, said flanges or partitions being engaged by corresponding notches in the key. On the ends of both longitudinal edges of said bolt there are lugs 4, which 80 bear against the inner faces of the body of the case and the cap thereof. One end of bolt C is provided with a tongue, 5, adapted to enter the notch b' in the reduced end b of the swinging arm of the shackle, and on the inner edges 85 of this tongue there are formed lips 6, constructed to embrace the portion of end b below said notch, thereby preventing any transverse motion of the swinging end of the shackle and locking it more securely with the 90 bolt. Adjoining tongue 5 on the upper face of bolt C there are studs or pins 7, and around these studs and between the same and the offset or shoulder formed by tongue 5, there is bent the head D of the flat bolt spring, the 95 leaves d of which extend lengthwise over the said upper face of bolt C, being prevented

from closing upon each other by a stay 8, formed on the end of the bolt opposite to that on which studs 7 are placed.

Stay 8 is not essential to the proper working of the bolt-spring, for when the vibrating ends of said spring meet the opening between them increases in width from said ends to the head D, leaving sufficient space between them for the introduction of the flat key used, but it facilitates the introduction of the key by increasing the opening between leaves d, and it is therefore preferable to employ it.

When the bolt C is engaged with the swinging end of the shackle the ends of leaves d, passing through slots e in walls E, abut against the inner edge of the "fast" end of the shackle and form struts that afford a positive resistance to the accidental disengagement of the bolt from said swinging end. In unlocking the shackle the key spreads the leaves d of the bolt-spring and frees the ends from engagement with the "fast" end of the shackle and as it moves the bolt back causes said leaves to embrace opposite sides of said "fast" end, recesses e' being formed in the body of the case and the cap to receive the ends of said leaves. In addition to the bolt spring there is a spring 12 coiled about a post 11 formed in the body of the case and passing over the reduced wall 9 and having one arm bearing against the wall E and the other against the back end of bolt C to force said bolt into engagement with the swinging end of the shackle.

The key-guide F is of a construction heretofore patented. In this lock the upper transverse part f forms a portion of the wall serving to hold the bolt C in place and also serves as a ward to engage corresponding notches in the key. In the front of this key-guide there is an annular recess f' in which there is a key-hole guard f², having a slot f³ through which the key passes.

On the side of the case in which the swinging end of the shackle is locked there is a plunger having an enlarged semi-circular head 13, which bears against the end of the swinging arm of the shackle and forces the same out of the case when released from bolt C. The stem 16 of the plunger passes through an opening 17 in the part 10 of the wall forming the bolt channel and has formed thereon, below said wall, a boss 18. Below said boss there is a circular extension, 19, of stem 16, around which there is coiled a spring 20, one end of which bears against boss 18 and the other against the bottom of a recess 21 formed in the bottom of the case. In the ends of the vertical edge of the plunger head there are formed notches 14, which engage ribs 15 in the body and cap of the case and thus control the movement of the plunger, which, to be fully effective must act vertically against the swinging end of the shackle.

The cap A' of the case is provided with walls 24, that register with the walls of key-guide F; and from one of these walls there

extends a wall or stay 25, which holds spring 12 down in place. There are also apertures 22 through cap A' adapted to be engaged by 70 the rivet pins a and a'.

Having thus described our invention, what we claim as new, and desire to secure by Letters Patent, is—

1. In a padlock, the combination, with a 75 bolt movable between the "fast" and swinging ends of the shackle, of a spring attached thereto having the vibrating end adapted to abut against the "fast" end of the shackle when the bolt is engaged with the swinging 80 end thereof and to lap said "fast" end when the bolt is disengaged from the swinging end of the shackle, substantially as and for the purpose specified.

2. In a padlock, the combination, with a 85 bolt movable between the "fast" and swinging ends of the shackle, of a spring attached thereto having the vibrating end adapted to abut against the "fast" end of the shackle when the bolt is engaged with the swinging 90 end thereof, the said vibrating end being constructed to lap said "fast" end as the bolt is disengaged from the swinging end of the shackle, and a spring engaging the bolt and forcing it into engagement with said swinging 95 end, substantially as and for the purpose specified.

3. In a padlock, the combination, with a shackle having one end pivoted in the case, of a bolt movable between the pivoted and 100 swinging ends of the shackle, walls formed in the case about the interior part of the space in which the shackle is pivoted and having a slot therein on the side toward the bolt, and a spring attached to the bolt and having 105 its vibrating end passing through said slot and adapted to abut against the pivoted end of the shackle when the bolt is engaged with the swinging end thereof, the said vibrating end being constructed to lap said pivoted end as the bolt is disengaged from the swinging 110 end of the shackle, substantially as and for the purpose specified.

4. In a padlock, the combination, with a locking-bolt having studs or pins on the face 115 thereof, of a spring bent around said studs or pins and having the leaves thereof adapted to abut against the edge of the "fast" end of the shackle and embrace the same as the bolt is disengaged from the swinging end of said 120 shackle, substantially as and for the purpose specified.

5. In a padlock, the combination, with a locking-bolt, of a V-shaped spring attached thereto, and a stay on the bolt located between the leaves of the spring, the ends of said spring being adapted to abut against the edge of the "fast" end of the shackle and embrace the same as the bolt is disengaged from the swinging end of said shackle, substantially as and for the purpose specified. 130

6. In a padlock, the combination, with a locking-bolt having studs or pins on the face thereof, of a V-shaped spring bent around

said studs or pins and having the leaves thereof adapted to abut against the edge of the "fast" end of the shackle, the said leaves being constructed to enter recesses in the 5 body and cap of the case and embrace said "fast" end of the shackle as the bolt is disengaged from the swinging end thereof, substantially as and for the purpose specified.

7. In a padlock, the combination, with a 10 shackle having a notch in the swinging end thereof, of a bolt having a tongue adapted to engage said notch, and lips on the tongue constructed to embrace the portion of the shackle forming a side of the notch, substantially as and for the purpose specified.

8. In a padlock, the combination, with a 15 longitudinally bisected case, of a bisected bottom plate having a portion of the key-hole formed in each section, registering semi-annular recesses formed in the sections of the bottom plate around and opening into the two portions of the key-hole, and an annular slotted key-hole guard revolvably engaging said recess, substantially as 20 and for the purpose specified.

portions of the key-hole, and an annular slotted key-hole guard engaging said recesses, substantially as and for the purpose specified.

9. In a padlock, the combination, with a 25 case bisected longitudinally through the edges, of a bisected bottom plate having a portion of the key-hole formed in each section, key-guides cast with the side and bottom plates of the case in each section thereof, 30 registering semi-annular recesses formed in the sections of the bottom plate around and opening into the two portions of the key-hole, and an annular slotted key-hole guard revolvably engaging said recess, substantially as 35 and for the purpose specified.
